US00D512091S

(12) United States Design Patent **(10) Patent No.:** **US D512,091 S**
(45) Date of Patent: **** Nov. 29, 2005**

(54) FONT OF SYMBOLS

(75) Inventor: **Hermann Zapf**, Heidelberg (DE)
(73) Assignee: **Heidelberger Druckmaschinen AG**,
Heidelberg (DE)
(**) Term: **14 Years**

(21) Appl. No.: **29/176,551**

(22) Filed: **Feb. 24, 2003**

(30) Foreign Application Priority Data

Aug. 24, 2002 (DE) 4 02 07 087

(51) LOC (8) Cl. **18-03**
(52) U.S. Cl. **D18/27**; D18/32; D18/33
(58) Field of Search D14/485-495;
D18/28-33, 24, 25, 27; 434/159; 101/398-399
